UNITED STATES PATENT OFFICE.

FREDERICK W. MARTIN, OF NEW YORK, N. Y., ASSIGNOR TO JOHN L. MOHUN, OF BROOKLYN, NEW YORK.

METAL ROOF FOR CARS.

1,155,596.

Specification of Letters Patent.

Patented Oct. 5, 1915.

Application filed December 19, 1912. Serial No. 737,767.

To all whom it may concern:

Be it known that I, FREDERICK W. MARTIN, a citizen of the United States, residing at the borough of Manhattan, in the city, county, and State of New York, have invented a certain new and useful Improvement in Metal Roofs for Cars, of which improvement the following is a specification.

This invention relates to metal roofs for cars, and has for its object to provide an improved joint construction for the adjacent side edges of the metal roofing sheets transversely of the car, by forming a substantially trough shaped depression at the edge 15 of one of the sheets, and bending the edge of the adjacent sheet, so as to drain into said trough. By this means the use of a separate drain trough located between the edges of the roofing sheets is avoided, and the joint 20 is rendered practically impervious to moisture, while at the same time permitting a certain amount of play between the roofing sheets to allow for flexibility of the roof.

In the accompanying drawing: Figure 1 25 is a transverse section showing one form of joint embodying my improvement; and Fig. 2, is a similar section showing my improvement employed with a trough shaped carline.

According to the construction shown in Fig. 1, the roofing sheets, 3, which are usually laid in a transverse direction across the car, are supported on a wooden substructure, 4, which may consist of roofing boards, 35 purlins, or other members. A lateral drain trough, 6, is formed at the side edge of one of the roofing sheets, 3, by turning up the extreme edge, 7, and forming an upward projection or rib, 5, spaced a short distance 40 from the up-turned edge, 7, and substantially parallel therewith.

The adjacent edge of the next roofing sheet is so formed as to drain into the trough, 6, by turning the edge of the sheet 45 upward at 8, then over and downward, as at 9, into the trough. Any water or moisture which may be driven over the rib, 5, from one side, or over the turned over edge, 9, from the other side, will fall into the trough, 50 6, and drain off at the eaves of the car. A sufficient clearance may be left between the projecting edge, 7, of one sheet, and the turned over portions, 8 and 9, of the adjacent sheet to permit of a slight relative

movement of said sheets, and thereby give 55 flexibility to the roof to allow for the weaving and twisting movement of the car during the running of the train.

For the purpose of protecting the trough and the overlapping edges of the roofing 60 sheets, a cap, 10, may be provided preferably in the form of an inverted U or trough having lateral flanges, 12, resting upon the roofing sheets.

If any rain or moisture is driven beneath 65 the flanges, 12, of the cap, it may drain off through the space between the side wall of the cap and the upwardly projecting portion of the roofing sheet, or if it should be driven in with sufficient force to be carried 70 over the projection, and fall into the trough portion, 6, such moisture may then drain off through said trough to the eaves of the car, and no water will pass through the joint between the roofing sheets into the 75 interior of the car.

As shown in Fig. 2, the roofing sheets are supported upon U shaped metal carlines, 11, and the edges of the roofing sheets with the trough, 6, are located over the channel of 80 the carline which would collect any moisture that should by any chance pass through the joint between the roofing sheets.

By means of this improved construction, in which the trough is formed in the edge 85 of the roofing sheets, the use of a separate part for this purpose is avoided, and the drain trough is always present at the proper position between the adjacent roofing sheets. This construction further serves to 90 strengthen the roof as the sheets are much stiffer at their edges.

Having now described my invention, what I claim as new and desire to secure by Letters Patent is:—

1. In a car roof, the combination with the supporting members, of transverse metal roof sheets with overlapping side edges, one sheet having a turned up edge and a vertical rib spaced apart to form a lateral drain 100 trough, and the edge of the adjacent sheet being turned up and over and down to drain into said trough, there being a free clearance space between the vertical portions of said overlapping edges and a metal cap portion 105 covering said trough.

2. In a car roof, the combination with a U shaped metal carline, of transverse metal

5 roof sheets with overlapping side edges, supported on said carlines, one roof sheet having a vertical rib and a turned up edge forming a drain trough over the channel in said carline, and the adjacent sheet being turned up and over and down to drain into said trough, and a metal cap covering said

trough, there being a free clearance space between said over-lapping edges.

FREDERICK W. MARTIN.
